UNITED STATES PATENT OFFICE.

BERRY A. BAXTER, OF MANSFIELD, OHIO.

STOVE.

SPECIFICATION forming part of Letters Patent No. 361,666, dated April 26, 1887.

Application filed December 9, 1886. Serial No. 221,061. (No model.)

To all whom it may concern:

Be it known that I, BERRY A. BAXTER, a citizen of the United States, residing at Mansfield, in the county of Richland and State of Ohio, have invented certain new and useful Improvements in Stoves; and I do hereby declare the following to be a full, clear, and exact description of the invention, such as will enable others skilled in the art to which it applies to make and use the same.

My invention relates to an improvement in stoves, and more particularly to that class of stoves in which the front is removable, and which are commonly known as "open-grate" or "fire-place" stoves.

Hitherto the removable front or blower has been constructed to be raised and lowered by a pair of counterbalanced sector-bars in engagement with rack-bars attached to the blowers near their edges, the rack-bars being connected with each other by a bar attached to the counter-weights and extending through curved slots in the ends of the stove.

The objection has been that the pressure of the sector-bars against the rack-bars in raising and lowering the blower has had a tendency to force the edges of the blower in close frictional contact with its front bearings, causing it to slide with a considerable resistance, due to the sliding friction; and, furthermore, when the teeth have become somewhat worn, there is a tendency of the blower to slightly tilt and bind, in addition to the liability of slipping a tooth on one side or the other and necessitating the removal of the sector-bar or the removal of the parts and their readjustment.

The object of my present invention is to provide blower-actuating mechanism which shall be free from the objectionable features of those hitherto in use, and which shall be simple and convenient.

A further object is to provide a pair of counterbalanced levers for actuating the blower, which shall be capable of automatically locking the blower in elevated adjustment, and which shall exert little or no lifting strain when the blower is depressed.

A further object is to locate the lever-actuating shaft in a cold-air chamber, and thereby lengthen its life.

With these ends in view my invention consists in certain features of construction and combinations of parts, as will be hereinafter described, and pointed out in the claims.

In the accompanying drawings, Figure 1 is a front view of a stove with the blower partially elevated. Fig. 2 is an end view with the outer wall broken away and the blower in depressed adjustment. Fig. 3 is a similar view with the blower in elevated adjustment, and Fig. 4 is a partial horizontal section in the plane of the lever-actuating shaft.

A A represent the inner end walls of the stove, in contact with which the fire-brick lining a is placed, from the bottom of the grate B as far up as the fuel is liable to be piled, as is usual.

The stove here represented is of rectangular shape in horizontal section and provided with an attractive top, C, extending down over the front a short distance, as shown. The grate D is made to project a short distance in front of the side walls, and the ash-pit E opens to the front on a plane with the hearth e. This, however, is only one of numerous forms of stoves to which my improvements are adapted, and they might be employed to advantage with a stationary fire-place grate, the side walls and hearth being modified to receive the blower and its actuating mechanism.

F represents the blower. It is constructed to slide up and down in front of the grate D, and when at its greatest elevation completely closes the front of the stove above the grate. It may be lowered to rest on the hearth at the bottom of the stove, or, as shown in the drawings, may pass down through a narrow slot, f, in the hearth and become hidden from view. Its edges, where they meet the edges of the stove-walls, are preferably formed V-shaped, as shown at G, in order to register with corresponding grooves, g, in the walls and prevent lateral displacement, and serve as guides to insure a regular movement in its passage up and down.

Between the inner walls, A, and the outer walls, H, at the ends of the stove, are located the counterbalance-levers I, firmly secured to a rock-shaft, K, extending through the stove from end to end. The levers I are provided on their front ends with smooth-faced sector-

bars *i* and on their rear ends with counterbalance-weights *i'*, preferably formed integral with the levers.

The upper ends of the smooth-faced sector bars *i* are connected to the edges of the blower by means of spring-metal bands *L*, the upper ends of which are attached directly to the sector-bars, and the lower ends of which are attached to the inner faces of the wings *m* on the 5 clips or ears *M*. The opposite wings, *m'*, of the said clips or ears are bolted, screwed, riveted, or otherwise secured to the edges of the blower. The outer faces of the wings *m* project behind the edges of the jambs *h* of the 10 walls *H*, and serve to lock the blower against outward displacement.

One end, *k*, of the rock-shaft *K* projects through the outer wall, *H*, and is squared or otherwise shaped to receive a crank or lever, 15 *N*, for rocking it. To prevent the shaft *K* from becoming exposed to the action of the flame and heat, and thereby becoming warped or burned out, the fire-back *O* of the stove is constructed to slant forwardly over the fire-pot, and after passing in front of the shaft *K* it recedes again to the rear of the smoke-flue. 20 The back *O* is provided with openings *o* at the top and bottom, to admit cold air into contact with the shaft *K*, the draft becoming naturally 25 established by the rise of the heated air at the rear of the fire-back *O*.

The protection of the shaft *K* is a matter of great importance to the perfect operation of the blower, as a slight warp or bend would be 30 liable to throw one or the other of the sector-bars *i* out of "true," and thereby tend to tilt the blower and cause it to bind.

When the blower is in depressed adjustment or lowered to its limit, the lever *I* will 35 not exert sufficient upward strain to raise the blower. When it is desired to elevate the blower, the shaft *K* is rocked by the lever *N* to start it, and as soon as the lever *I* becomes slightly tilted the weight *i'* will begin to assist, and will so continue to do until the blower reaches its elevated adjustment, as 40 shown in Fig. 3. The tendency of the weighted end of the lever *I* will then be exerted to automatically lock the blower in its elevated adjustment. The strain of the bands or ribbons *L* will be even and continuous on the blower. 45 There will be no tendency to wear and loosen, as in the case of intermeshing teeth. The movements of the parts will be attended with 50 very little noise, and the forward bend of the fire-back will accomplish the double purpose

of reflecting additional heat into the room and of forming a convenient protection for the lever-actuating shaft.

It is evident that slight changes might be resorted to in the form and arrangement of the several parts described without departing from the spirit and scope of my invention; hence I do not wish to limit myself strictly to the construction herein set forth; but, 60 65

Having fully described my invention, what I claim as new, and desire to secure by Letters Patent, is—

1. The combination, with a fire-chamber permanently closed on three sides and the top, 70 of a vertically-movable blower and a pair of counterbalanced actuating-levers connected with the blower by bands, whereby the blower is raised and lowered in front of the fire-chamber, substantially as set forth. 75

2. The combination, with an open-front stove and a blower adapted to rise and fall in front of the stove, of a pair of counterbalanced levers mounted at the ends of the stove and having curved ends attached to the edges 80 of the blower by flexible metallic bands, substantially as set forth.

3. The combination, with an open-front stove and a blower adapted to rise and fall in front of the stove, of a pair of counterbalanced levers located at the ends of the stove and centered on a rock-shaft extending through the stove, the ends of the levers being connected with the blower, substantially as set forth. 85 90

4. The combination, with the blower, of the actuating-levers having smooth curved ends and the flexible metallic bands connecting the ends and the blower, substantially as set forth.

5. The combination, with the vertically-movable blower and the blower-actuating levers located in recesses between the end walls of the stove, of the lever-supporting shaft extending through a cold-air chamber at the back of the stove, substantially as set forth. 95 100

6. The combination, with the vertically-movable blower and the blower-actuating levers, of the locking-ears secured to the sides of the blower and the flexible metallic bands connecting the ears with the actuating-levers, 105 substantially as set forth.

In testimony whereof I affix my signature in presence of two witnesses.

BERRY A. BAXTER.
